UNITED STATES PATENT OFFICE.

LEON MEUNIER, OF CLEVELAND, OHIO, ASSIGNOR TO CHICAGO PNEUMATIC TOOL COMPANY, OF NEW YORK, N. Y., A CORPORATION OF NEW YORK.

GOVERNOR FOR FLUID-PRESSURE TOOLS.

Application filed May 6, 1922. Serial No. 558,967.

To all whom it may concern:

Be it known that I, LEON MEUNIER, a citizen of the United States, residing at Cleveland, in the county of Cuyahoga and State 5 of Ohio, have invented certain new and useful Improvements in Governors for Fluid-Pressure Tools, of which the following is a specification.

My invention relates to governors for 10 controlling fluid pressure tools, such, for example, as pneumatic drilling, reaming and tapping machines, and the like. The principal object of my invention is to provide an improved and efficient governor which 15 will permit a maximum supply of air or other motor fluid to be admitted to the tool while the latter is under load, that is, performing work for which it is designed, and will automatically reduce the supply of air 20 admitted to the tool when it is relieved of its load, such as when the tool is moved out of working engagement with the work upon which it is operating. When a pneumatic tool is moved out of engagement with the 25 work, there is a tendency for it to race or unduly accelerate its speed because it has been relieved of its load or resistance, and this racing is obviously objectionable as it results in excessive and violent vibration of 30 the tool and in some cases breakage of the parts, as well as an uneconomical consumption 35 of the motive fluid. My invention in general comprises a main valve and an auxiliary or controlling valve constructed 40 to automatically permit the maximum volume of air to be supplied to the pneumatic tool when the latter is in actual contact with the work and automatically reduce the volume of air supplied to the tool 45 when the latter is moved out of engagement with the work.

Referring to the drawings, Fig. 1 is a central longitudinal section through a governor embodying my invention; Fig. 2 is a 50 cross section on the line 2—2 of Fig. 1; Fig. 3 is a view like Fig. 1 except that the governor is in the condition which it assumes when the maximum supply of air is being admitted to the pneumatic tool; Fig. 4 is a section taken on the line 4—4 of Fig. 1; Fig. 5 is a plan elevation of a fragment of the device for operating the throttle valve, and Fig. 6 is a detail longitudinal section taken on the line 6—6 of Fig. 2.

My invention broadly comprises a casing

10 provided with three valve chambers 11, 12, and 13; a manually controlled throttle valve 14 in the valve chamber 12; valve mechanism in the chamber 11 comprising a differential sleeve piston 15 and a cooperating valve member 16; a compound valve mechanism in the chamber 13 comprising a differential piston 17 and a sleeve valve 18; and suitable ports and passages controlling and controlled by the valve mechanisms. 60

The valve chambers 11 and 13 are parallel to each other, the chamber 13 being directly under the chamber 11, and the chamber 12 is in alignment with the chamber 11, being formed by a tubular extension 19 of the 70 casing. The rear end (that is, the right-hand end as viewed in Figs. 1 and 3) of the extension 19, forming the valve chamber 12, is provided with a nipple or connection 20 to which the flexible hose leading from the 75 source of air supply is adapted to be connected and through which the air enters the governor. A nipple or connection 21 is screwed into the forward end (that is the left-hand end as viewed in Figs. 1 and 3) 80 of the chamber 11, the one end of a hose extending to the pneumatic tool being adapted to be connected to the nipple which forms the outlet for the air passing through the governor. The forward end of the 85 chamber 13 is closed by a screw plug 22.

The throttle valve mechanism is manually controlled, this valve being employed to control the volume of air to be supplied to the tool, at the will of the operator. The valve 90 14 reciprocates in a bushing or sleeve 24 fixed in the tubular extension 19 in any desired manner. The rear end of the valve 14 is provided with a head 25 adapted to seat against a beveled seat 26 on the rear end 95 of the bushing 24. A passage extends longitudinally through the cylindrical part of the valve 14 within the bushing 24, this passage being formed by a forward central bore 28, a central semi-circular transverse 100 groove 29 and a transverse side groove 30 in alignment with the groove 29. A pin 31 screwed into the valve 14 projects through aligned longitudinally-extending slots 32 in the bushing 24 and the extension 105 19 and its outer end extends into a cam slot 33 formed in an operating sleeve 34 encircling the extension 19 and confined between a shoulder thereon and the flange on the connection 20. When the sleeve 34 is 110

in the position shown in Figs. 1 and 5, the head 25 is spaced from the seat 26 and this throttle valve is then wide open. When the sleeve 34 is rotated to bring the opposite 5 end of the slot 33 into engagement with the pin 31, the slot through the pin shifts the valve 14 forwardly to move the head 25 into engagement with the seat 26, and thereby cut off the supply of air through the main 10 valve of the governor and to the pneumatic tool.

The differential sleeve piston 15 slides in a sleeve or bushing 36 fixed in the chamber 11. The sleeve 36 is counterbored to form 15 two cylinders, in the larger of which the enlarged forward end of the piston 15 fits and slides while the smaller portion of the piston fits and slides in the smaller cylinder. An integral partition 37 is located at the 20 forward end of the piston chamber 12, and this partition is provided with a plurality of holes 37'. The cone-shaped valve member 16 is mounted centrally on the partition by a pin 38. The diameter of the valve 16 25 is but slightly less than the diameter of the opening 40 in the rear end of the sleeve piston 15. When the piston 15 is in the position shown in Fig. 1, the valve 16 being located in the opening 40 permits but a 30 small supply of air to pass through the pneumatic tool, the tool at such time being out of engagement with the work. When the sleeve piston 15 is moved rearwardly to the position shown in Fig. 3, at the time the 35 pneumatic tool is moved into engagement with the work and the load is thereby put on the tool, as will be described presently, the valve 16 is positioned in the enlarged central portion of the passage through the sleeve 15 so that the valve member 16 does 40 not restrict the flow of air through the governor and to the tool, the maximum supply of air to be then admitted to the tool.

The operation of the sleeve piston 15 is 45 controlled by the differential piston 17 and the slide or sleeve valve 18. The piston 17 comprises the two heads 42 and 43 connected by the rod or bar 44. Each head is provided with a piston ring 45 to prevent 50 leakage of the air around the respective heads. Rearward movement of the piston is limited by engagement of a projection 46 on the head 43 against the rear end of the chamber 13 and forward movement of the 55 piston is limited by engagement of the projection 47 on the head 42 with the plug 22. The piston 17 slides in a sleeve 49, fixed in the chamber 13. This sleeve 49 has internal diameters or bores forming piston cylinders 60 of different diameters, the piston head 42 being fitted in the larger cylinder and the piston 43, which is smaller in diameter than the piston head 42, fitting in the smaller cylinder. The sleeve valve 18 is formed in 65 two parts, as shown in Figs. 1 and 2, so

that it can readily be assembled on the rod 44. Coiled springs 52 are compressed and seated in recesses in the confronting edges of the two parts to firmly press the halves of the sleeve into firm engagement with the 70 bushing 49. A screw plug 53 (Fig. 2) having an extending pin 54 is screwed into the side of the casing and the pin 54 projects between the two halves of the sleeve of the valve 18 to prevent rotation of the valve 75 while permitting axial movement thereof relative to the piston rod 44. The ports and passages controlled by the differential pistons 17 and the sleeve valve 18, for controlling operation of the sleeve piston 15, will 80 be described in connection with the description of the operation of the device now to be given.

Assuming that the pneumatic tool is out of engagement with the work and that the throttle valve 14 has been moved to open position, the valve mechanisms are then in the condition shown in Fig. 1, the pistons 15 and 17 being in their forward positions. The piston 15 is maintained in this position 85 by the air pressure in the chamber 11^a, which constitutes the rear end of piston chamber 11, and the piston 17 is maintained in its forward position by the pressure of air in the chamber 13^a, which constitutes the 90 rear end of the piston chamber 13, the air being admitted to such chamber 13^a through a passage 55 in the casing 10 and a coincident longitudinal groove 56 formed in the bushing 24. The sleeve valve 18 covers a 95 port 57 in registry with the passage 58 in the casing 10 and the rear end of the passage 58 is in registry with a port 59 in the bushing 49. At the same time a port 60 in the bushing 49 is uncovered by the head 42 100 of the differential piston 17 and the port 60 is in registry with a passage 61 formed in the casing 10 and the bushing 36. The rear 105 end of the passage 61 is in communication with a port 62 in the bushing 36 and with an aligned port 63 in the bushing 49. Therefore a chamber 64, formed between the confronting faces of enlarged portions 110 of the bushing 36 and the sleeve 15, is vented through the port 62, passage 61, the port 60, 115 the interior of the bushing 49 and an exhaust port 65 formed in bushing 49 and the casing 10.

When the pneumatic tool is moved into engagement with the work upon which it 120 is to operate, the speed of the tool is retarded due to the resistance which it meets and therefore the air pressure in the spaces or chambers at the forward ends of the sleeve 15 and the head 42 and indicated by 125 the reference numerals 11^b and 13^b is increased. The chamber 13^b is in communication with a groove 66 formed in the connection or nipple 21 and communicating 130 with the central bore of the nipple through

transverse passages 67. This increase of air pressure in the chamber 13^b shifts the piston 17 rearwardly to the position shown in Fig. 3, in which position the annular space 5 around a shoulder 69 on the piston 17 is in alignment with the port 65 and an annular groove 68', which with a passage 68 opening therein is formed in the head, is in alignment with the port 60, so that the above 10 mentioned chamber 64 between the piston 15 and bushing 36 is vented through the head 42. During such movement of the piston 17, the shoulder 69 thereon engages the forward end of the sleeve valve 18 and 15 moves the latter to the position shown in Fig. 3 in which the ends of its passage or groove 70 are in registry with the ports 57 and 63. The increased pressure in the chamber 11^b being greater than the pressure in 20 the rear chamber 11^a shifts the piston sleeve 15 to the position shown in Fig. 3, the chamber 64 being vented as above described to permit the shifting movement. In this position of the piston 15, the maximum volume 25 of air is permitted to flow to the pneumatic tool, the valve 16 being in unobstructing or unrestricting position with respect to the sleeve 15.

Now when the tool is moved out of engagement with the work, the air pressure in 30 the chambers 11^b and 13^b decreases as the tool is relieved of the resistance and it tends to accelerate its speed, with the result that the air pressure in the chambers 11^a and 13^a 35 is now greater than that in the chambers 11^b and 13^b. This results in forward movement of the piston 17 to the position shown in Fig. 1. During the initial movement of the piston 17 it moves relative to the sleeve 40 valve 18 and at the instant the head 43 moves into engagement with the rear edge of the valve 18, the head 43 uncovers the port 59, whereupon the live air supplied to the chamber 13^a through the passages 55 45 and 56, passes through the port 59, the passage 58, port 57, passage 70, and ports 63 and 62 to the chamber 64, wherein the air pressure on the pressure area 72 of the sleeve piston 15 together with the air pressure 50 in the chamber 11^a shifts the piston 15 to the position shown in Fig. 1, thereby again restricting the flow of air to the pneumatic tool. At such time the head 42 covers the port 60 so that the air cannot escape 55 from the chamber 64. Then upon continued movement of the piston 17, to the position shown in Fig. 1, the sleeve 18 is moved to the position shown in this figure and this completes the cycle of operation.

60 While I have herein described in some detail the particular embodiment of my invention, for the purposes of full disclosure, it will be understood by those skilled in the art that many changes in details might be 65 made without departure from the spirit or

scope of my invention hereinafter defined. While I have defined my invention as being adapted for use in connection with tools operated by air, it is obvious that the governor may be used with and operated by other 70 motive fluid, and in connection with various tools and devices intended for different uses.

I claim:

1. In a governor of the class described, a 75 main valve and a differential valve for controlling the same, said differential valve having a pressure area constantly subjected to live motive fluid.

2. In a governor of the class described, a 80 casing having a valve chamber, and a valve comprising a sleeve piston through which the supply of air passes and a stationary member cooperating with the bore of the piston to control the supply of air. 85

3. In a governor of the class described, a 90 casing having a valve chamber, a sleeve piston having a passage through the same with the entrance thereto restricted, a valve member positioned in said passage, and means for effecting relative movements between said sleeve and member to position the member in said entrance when the supply of air is to be restricted and position it within the enlarged portion of the passage when 95 the supply of air is to be increased.

4. In a governor of the class described, a 100 sleeve piston having a central passage with a restricted entrance through which the supply of air passes, a stationary valve member, and valve mechanism controlling the shifting of said piston so that said member is in the entrance of the passage when the supply of air is to be restricted and within the large portion of the passage when the supply of air is to be increased. 105

5. In a governor of the class described, a 110 sleeve piston having a central passage through which the supply of air passes, a member cooperating with said sleeve to vary the supply of air, and valve mechanism controlling a passage to expose a pressure area on the piston to air pressure for the purpose of moving it in one direction.

6. In a governor of the class described, a 115 valve comprising a differential piston and a member cooperating therewith to control the supply of air, said valve having three pressure areas two of which are opposed and constantly exposed to the air pressure, and a valve mechanism controlling a passage through which the third pressure area is exposed to air pressure. 120

7. In a governor of the class described, a 125 sleeve piston having a larger pressure area on one end than the other and an intermediate pressure area, a member cooperating with a passage through the piston to control the supply of air, and a valve mechanism for controlling the air pressure on said third 130

- ply of motive fluid passes and a stationary member cooperating with said piston to control the motive fluid supply, said piston having at its ends opposed pressure areas exposed to the fluid pressure in the opposite ends of the casing and an intermediate pressure area, and an auxiliary valve mechanism controlling an air passage leading to said intermediate pressure area.
- 10 21. In a governor of the class described, a casing having a valve chamber, a main valve including a sleeve piston through which the air supply passes and having its opposite ends of different areas exposed to the air pressures in the opposite ends of the casing and an intermediate pressure area, and an auxiliary valve mechanism controlling an air passage leading to said intermediate pressure area.
- 15 22. In a governor of the class described, a casing having two valve chambers, a main valve in one chamber including a movable member having pressure areas exposed to the air pressures in opposite ends of such chamber, an auxiliary valve in the other chamber having means controlling the main valve and having pressure areas exposed to the air pressures in the opposite ends of such chamber, and passages connecting the corresponding ends of the two valve chambers.
- 20 23. In a governor of the class described, a casing having two valve chambers, a main valve in one chamber including a movable member having opposed pressure areas of different extents constantly exposed to the air pressures in the opposite ends of such chamber and a third pressure area, and an auxiliary valve mechanism in the second chamber including a movable member controlling an air passage leading to said third pressure area and having two pressure areas constantly exposed to the air pressures in the opposite ends of the second chamber.
- 25 24. In a device of the class described, a casing having a valve chamber, and a valve mechanism therein comprising a differential piston and a sleeve thereon formed of two parts with spring means between the same, said sleeve having a lost motion connection with said piston.
- 30 25. In a device of the class described, a casing having a valve chamber, a valve mechanism therein comprising a differential piston and a sleeve thereon having a lost motion connection with said piston.
- 35 26. In a device of the class described, a casing having a valve chamber, a valve mechanism therein comprising a differential piston and a sleeve thereon having a lost motion connection with said piston and controlling at least one port in said casing.
- 40 27. In a device of the class described, a casing having a valve chamber, and a valve mechanism therein comprising a differential piston and a sleeve thereon formed of two parts with spring means between the same, said sleeve having a lost motion connection with said piston and controlling at least one port in said casing.
- 45 28. In a device of the class described, a casing having a valve chamber, and a valve mechanism therein comprising a differential piston and a sleeve thereon formed of two parts with spring means between the same, said sleeve having a lost motion connection with said piston and controlling ports and passages in said casing and a projection on the casing extending between the two parts of the sleeve to permit reciprocation and prevent rotation of the sleeve.
- 50 29. In a device of the class described, a casing having a valve chamber, a piston therein having two heads connected by a rod, the opposite ends of the heads being exposed to the air pressures in the opposite ends of said chamber, a two-part sleeve on said rod, resilient means between the two parts of the sleeve and a stationary projection extending between the two parts.
- 55 30. In a device of the class described, a casing having a valve chamber, a piston therein having two heads connected by a rod, the opposite ends of the heads being exposed to the air pressures in the opposite ends of said chamber, and a sleeve on said rod, said sleeve being of less length than said rod whereby a lost-motion connection is established between said sleeve and piston.
- 60 31. In a device of the class described, a casing having a valve chamber, a piston therein having two heads connected by a rod, the opposite ends of the heads being exposed to the air pressures in the opposite ends of said chamber, and a sleeve on said rod controlling at least one port in said casing, said sleeve being of less length than said rod whereby a lost-motion connection is established between said sleeve and piston.
- 65 32. In a governor of the class described, a casing having three valve chambers, a throttle valve in one chamber, a main governor valve in another chamber, and an auxiliary valve in the third chamber for controlling said main valve, and an air passage by-passing said throttle valve and opening into said third chamber.
- 70 33. In a governor of the class described, a casing having a valve chamber, and a piston sleeve valve therein through which the supply of air passes, moved in opposite directions by air pressure and having one pressure area exposed to the pressure of air entering the governor and another pressure area exposed to the pressure of air passing out of the governor.

LEON MEUNIER.
